UNITED STATES PATENT OFFICE.

DEXTER W. PARKER, OF MERIDEN, CONNECTICUT.

EXTENSION-CHANDELIER.

SPECIFICATION forming part of Letters Patent No. 278,359, dated May 29, 1883.

Application filed March 13, 1883. (No model.)

To all whom it may concern:

Be it known that I, DEXTER W. PARKER, a citizen of the United States, residing at Meriden, in the county of New Haven and State of Connecticut, have invented certain new and useful Improvements in Extension-Chandeliers; and I do hereby declare the following to be a full, clear, and exact description of the invention, such as will enable others skilled in

10 the art to which it appertains to make and use the same, reference being had to the accompanying drawings, and to letters or figures of reference marked thereon, which form a part of this specification.

15 This invention is an improvement on my Patent No. 269,105, granted December 12, 1882; and it consists, chiefly, in means for automatically actuating the clamping-wedge therein shown and described, the said means 20 serving also for the suspension of the movable part of the extension-chandelier, as hereinafter set forth.

It further consists in certain details of construction and combination, which will be stated 25 in the appended claims.

In the accompanying drawings, Figure 1 represents a vertical section of a chandelier embodying my present invention; and Fig. 2 represents a perspective view of the canopy or 30 hanger and the devices within the same.

A designates the center box of a chandelier, to which the arms B are attached, and which is hung on the movable tube C, that slides over the solid upper part or rod, D, of the fixture. 35 This rod is secured to canopy or hanger E, and the latter is provided with an eye or stirrup, F, at the upper end of an arm, G, whereby the chandelier is hung, as usual, to a hook driven into a ceiling or screwed on the end of a gas- 40 pipe extending downward therefrom. All the attachments above referred to are preferably made detachable.

The devices for clamping the bottom plate of the center box against the chandelier-arms 45 and for allowing the free vertical movement of the finger-bar need not be described here, as they differ but little from those shown and claimed in a pending application.

The incline case G' on the upper end of tube 50 C is constructed and arranged substantially as in my Patent No. 269,105, above mentioned,

and the shoe H and wedge I operate substantially on the same principle as in that patent, although the inner face of said shoe is provided with serrations h to give it a better hold 55 on the rod D. The cord K, which is the means of connection between said wedge and the finger-bar L, extends down through tube C, as in said patent, and is used for the same purpose; but instead of attaching its upper end directly 60 to the wedge I it is attached to the lower inwardly-bent end, i, of a rod, I', extending down from said wedge. This end i passes through a vertical slot, e, in the upper end of tube C. This construction of said parts allows said tube 65 to be made of smaller diameter than would otherwise be practicable. In said patent the wedge is shown as forced upward by a small spring surrounding the cord or rod K and within the movable lower tube. Of course said 70 spring has no effect in sustaining the tube itself. In my present invention, however, I employ a strong clock-spring, M, arranged within a revolving barrel, N, which turns on a shaft or bar held in supports O within the canopy 75 or hanger E. A chain, P, is attached at its upper end to said barrel and at its lower end to said wedge. The stress of the spring on said chain tends not only to lock the outer tube and the inner rod together, but to prevent the 80 former from falling. When the cord K is drawn upon from below, the spring is overcome and the wedge temporarily dislodged. There is then neither frictional nor resilient resistance to the descent of the tube C. When the 85 operator releases the cord the spring M resumes its duties both as an automatic clamp-operating device and as a suspending device.

To make the pull of the chain P vertical a guide-pulley, Q, is employed, which turns in 90 bearings in the lower part of the canopy at a point almost directly over the wedge. The chain passes up through a slot or opening in the bottom of said canopy to the inner side of said pulley, then over the top of the same, and around the barrel N. As this chain is fully exposed to view, the extension-fixture cannot be turned or twisted in any way without detection. It thus constitutes a gage for determining the accuracy of arrangement of the other devices 95 forming part of the extension-chandelier, and, being outside of the central line of upright de-

vices, is, moreover, preserved from the twisting and straining which often injure cables and chains that pass down within the tube.

The construction above described is cheaper than the common one, which uses an inside slotted tube and a middle tube having a stud or studs moving in said slots, since this latter construction requires an extra incasing-tube to conceal the unsightly slot and stud. The ends of the slotted tube also have to be made solid, which involves additional expense.

Of course the clock-spring is better protected than helical or other unincased springs would be. The solid upper rod is better than a tube, although the latter may be used instead.

The devices described in the foregoing specification may be used with extension-lamp fixtures as well as with chandeliers.

What I claim as new, and desire to secure by Letters Patent, is—

1. A clock-spring and revolving barrel located in a chandelier-canopy, in combination with the movable lower tube of the chandelier, and a chain attached to said barrel, by which said movable tube is suspended, the construction and arrangement of the parts being such that the said chain passes in proximity to the stationary part of the chandelier-fixture, but outside thereof.

2. A chandelier-canopy having a guide-pulley journaled in its slotted bottom, in combination with a clock-spring and revolving bar-

rel located within said canopy, and a chain attached at its upper end to said barrel and suspending the movable part of the chandelier from its lower end, said chain being guided by said pulley on the inner side of the latter, so as to be in proximity to the upper part of the chandelier-fixture, though exterior thereto.

3. In combination with the movable part of a chandelier and the wedge which locks it to the fixed part thereof, a spring and chain which operate on said wedge to lock the parts of the chandelier together, and also to suspend the lower part thereof, the parts being so arranged that the chain will be outside of said chandelier, though in proximity thereto.

4. A canopy and a clock-spring, barrel, and guide-pulley, the latter being journaled in the bottom of the canopy, in combination with a fixed upper part of a chandelier-fixture, a movable tube, to which the center box is attached, and a chain which extends from said barrel to said movable tube and is guided by said pulley so as to pass in proximity to the chandelier, but outside thereof, substantially as set forth.

In testimony whereof I affix my signature in presence of two witnesses.

DEXTER W. PARKER.
